Original application May 20, 1932, Serial No.
612,624. Divided and this application February
26, 1934, Serial No. 713,047

2 Claims. (Cl. 74—305)

This invention relates to starting mechanism for internal combustion engines, and more particularly to starters of the power turning gear type.

An object is to provide an engine starter or other turning gear embodying novel means for holding the cooperating elements of the torque multiplying gear train in assembled relation.

In transmitting torque from a source to a stationary member, a strain is placed upon the parts of the latter at the moment it is started and at moments when a sudden change in load occurs. These strains endanger the life of such stationary member as well as the operation of the entire plant. It is, therefore, a further object of the present invention to provide, in conjunction with the torque multiplying means above referred to, novel mounting means for an engine accessory whereby torque reaction between the engine and said accessory is yieldingly resisted; said accessory being adapted for movement as a unit relative to said engine.

For claims to such accessory mounting means, per se, reference is to be had to my Patent No. 1,979,162 issued as a result of application No. 612,624, filed May 20, 1932, of which application the present one is a division.

A still further object is to provide an engine starter which is rugged in construction, inexpensive to manufacture, and particularly adapted for use with small aviation engines.

The above and further objects and novel features of this invention will more fully appear from the following detailed description when taken in connection with the accompanying drawing wherein one embodiment of the invention is illustrated. It is to be expressly understood, however, that the drawing is for the purpose of illustration only and is not designed as a definition of the limits of the invention, reference being had for this purpose to the appended claims.

The drawing is a side elevational view, partly in section, of an engine starting device constructed according to the present invention.

The illustrated embodiment of the present invention shows, by way of example, an engine starter yieldingly mounted on the crankcase 4 of an internal combustion engine, said starter comprising driving means such as an electric motor 5 adapted to rotatably drive a starter jaw clutch member 6 through suitable gearing to be hereinafter described in detail. The starter jaw 6 is adapted to be moved axially into and out of engagement with a complementary jaw 8 mount-

ed on the crankshaft 9, or an extension thereof, of an engine, whereby said crankshaft may be rotatably driven and the engine started.

The starting unit as shown is provided with suitable housing means comprising a main housing member 10 adapted to be removably secured in a novel manner to the crankcase 4 and a motor housing 11 rigidly attached to the outer face of said main housing member by means of a plurality of elongated bolts, one of which is shown at 12. The extended portion of shaft 13 of motor 5 is rotatably supported in a suitable bearing 14 which is in turn mounted in the central hub portion of a transversely disposed wall or spider 15 that may be securely held in engagement with the inner end of housing 11 by means of bolts 12.

Suitable torque multiplying means, including a simple and efficient reduction gear train, and novel supporting means therefor, has been provided to transmit the power of motor shaft 13 to a driven member at a reduced speed with increased torque. The gear train, as shown, comprises a compound planetary gear member or pinion 16 having two sets of teeth 17 and 18 cut thereon, the diameter and number of teeth of one set being somewhat less than those of the other set, and said member being rotatably mounted as by means of bearings 19 on a sleeve 20 which surrounds a supporting pin 7 whose threaded ends engage two discs or rings 21 and 22 secured by means such as bolts 23 for rotation as a unit about the axis of shaft 13. Rings 21 and 22 are rotatably mounted on shaft 13 by means of bearings 24, the entire unit being retained on shaft 13 by a nut 25 on the reduced end portion of said shaft. If desired, three gear members 16 may be employed, spaced 120 degrees apart and mounted in the manner shown. Preferably the bolts 23 are of the same number, and spaced to alternate with the pinion supporting shafts (pins) 7.

The construction just described has the advantage that the bearings 19 absorb the axial thrust as well as the radial pressure.

The larger portion 17 of member 16 is in constant mesh on one side with a pinion 26 suitably splined or keyed to shaft 13, and on its other side with a stationary internally toothed annular gear 27 secured between spider 15 and housing 10 by bolts 12. The smaller portion 18 of member 16 is in constant mesh with gear teeth cut on the inner periphery of a bell shaped member 28 formed integrally with an inwardly extending hub portion 29 which is rotatably mounted in housing member 10 by means of suitable bearings 55

30 and 31. Appropriate means for maintaining these bearings in proper position may include a ring 32, a spacer 33, and a nut 34 threaded to the inner end of hub 29.

5 Suitable means are provided for drivably connecting gear member 28 to the starter jaw 6 in such a manner that the jaw may be moved into and out of mesh with the engine jaw 8. Preferably, such means is constituted by a jaw clutch 10 assembly consisting, as shown, of a shaft 35 threaded into the hub portion 29 of gear member 28 and provided with longitudinal splines at its outer end to receive the interiorly splined tubular portion of starter jaw 6. Secured to the 15 inner end of shaft 35 is a stop nut 36 for limiting the outward movement of said shaft with respect to hub 29. Relative axial movement between starter jaw 6 and shaft 35 is limited by rod 37 extending through central openings in 20 each of these members. Preferably, a spring 38 surrounds the engine end of rod 37 bearing at one end against the inner face of starter jaw 6 and at its other end against the threaded shaft 35, the latter being provided with a recess into 25 which a portion of spring 38 extends. The starter jaw 6 may be maintained on rod 37 by means of a nut 39 threaded thereon.

30 Preferably, automatic means are provided for insuring the meshing of the starter jaw 6 with complementary jaw 8 associated with the engine crankshaft 9. As shown, such means include a light metal housing 40 which is rigidly held in place by means of an annular shelf 41 on a member 42, further to be described. In the particular structure illustrated, three arcuate members 42 surround the starter jaw 6 and are rotatably supported in an annular semi-circular channel 43 formed by outwardly bending the inner edge of housing member 40, each arcuate member 40 having a bead which rests in said channel. A toroidal spring 44 received by grooves in the outer periphery of members 42 is provided for exerting an inward pressure on said members, thereby maintaining them in frictional engagement with housing 40. Each of the members 42 is provided with a suitable lug or projection 45 which extends inwardly into a corresponding axial slot 46 in the outer periphery of starter jaw 6, thereby permitting relative axial movement between said jaw and members 42. Upon energization of the motor, rotation of starter jaw 6 is retarded by members 42 which slide in channel 43, whereupon the starter jaw moves inwardly into mesh with the jaw 8 by virtue of 55 the coaction of the screw threads on shaft 35 and hub 29. Preferably, the jaws 6 and 8 are provided with inclined teeth so that there will be an immediate disengagement of the starter jaw when its speed of rotation is exceeded by 60 the engine jaw 8, that is, when the engine commences firing.

65 Means are provided for yieldingly mounting the above described starting unit, or similar apparatus, on the crankcase of an engine, in a manner such that the entire unit is adapted for limited movement in its pilot bearings relative to the crankcase, whereby any shock produced by a sharply changing torque or load is absorbed by suitable yielding means, thus preventing injury to and strain upon the mechanism. In the 70 preferred embodiment shown, the housing 10 is provided at its inner face with an annular flange 47 which has cut therein a plurality of arcuate pilot slots 48 concentric with the axis of rotation of the starter mechanism and through which

slidably extend supporting or pilot members such as stud bolts 49 threadedly received by the crankcase 4. Surrounding the outer portions of bolts 49 are coil springs 50 interposed between the outer face of flange 47 and adjusting nuts 51 threaded onto the outer ends of said bolts. It is thus seen that the starter is held firmly against the crankcase by the pressure of springs 50 but is at the same time capable of limited axial movement relative thereto. Limited rotary movement is also possible, due to slots 48 above described, and such movement is yieldingly resisted by coil springs 56 provided in laterally-extending ears 52 (preferably two, diametrically disposed) the central axes of which are substantially perpendicular to the axis of rotation of the starter unit. Extending through the ears 52 are bolts 54 which are supported at their ends in any suitable manner such as by brackets 55 integral with or rigidly attached to the engine crankcase 4. Normally the ears 52 are centrally positioned on the bolts 54, and the coil springs 56 surrounding said bolts on each side of said ears abut brackets 55. For assisting in the support and proper seating of the forward end of the starter housing, the annular shelf or abutment 41 aforementioned, has an outer face beveled at an angle permitting it to rock on the beveled annular opening 57 in the crankcase 4.

5 In operation, the motor 5 is energized from a suitable source of electrical energy (not shown) whereupon the shaft 13 rotates with the motor armature, and its motion is in turn transmitted through pinion 26, planetary gears 17, 18 and internal gear 28 to the hub 29. During the initial rotation of the hub 29, starter jaw 6 and shaft 35 are retarded by virtue of the frictional relation between arcuate members 42 and housing member 40, thereby causing relative rotation between hub 29 and shaft 35, whereupon the screw threads of said two last named members coact and cause shaft 35 to move to the left, carrying starter jaw 6 into mesh with engine jaw 8. It will be noted that the speed of rotation of the starter jaw at the instant of meshing is comparatively slight, thereby preventing a clashing of the jaw teeth. As soon as the said jaws have been brought into engagement, thereby establishing a positive driving connection between the starter and the engine, the members 42 commence rotating with the starter jaw 6 and continue to do so during the cranking operation. As soon as the engine fires and the speed of engine jaw 8 exceeds that of the starter jaw 6, the latter is moved to the right by virtue of the inclined teeth.

6 As pointed out above, the inertia of the movable engine parts of the engine places a large sudden load upon the starter at the instant jaw 6 is engaged with jaw 8. As this sudden load is placed upon the starter, certain of the springs 56 yield and allow the engine starting unit to rotate bodily by reason of the pilot slots 48, thus preventing any sudden shock or strain upon the starter gearing and the motor. In like manner, these springs, aided by the resilient members 55, will absorb any shock occasioned on the backfire of an engine and all variations in the load which may be placed on the driving unit.

7 There has thus been provided a novel engine starting mechanism which includes a simple and efficient compound gear train and which is well adapted for practical use, which may be easily and cheaply constructed and assembled from rugged parts, thus reducing the possibility of fall-

ure of such parts and facilitating overhaul. Novel means have also been provided in combination with said starter for yieldingly mounting the same on the crankcase of an engine to be started thereby protecting the parts thereof against sudden shocks and excessive or changing loads.

5 What is claimed is:

10 1. In a device of the class described, the combination of a driving gear constituting the center of a planetary system, a planet carrier rotatable around said center, fixed and rotatable orbit gears surrounding said carrier, a planet pinion meshing with said orbit gears, said planet pinion having a straight walled pocket in each end face, and means adapted to roll along and in contact 15 with the straight walls of said pinion pockets to

transmit to said carrier the axial component of the forces imposed upon said pinion.

2. In a device of the class described, the combination of a driving gear constituting the center of a planetary system, a planet carrier rotatable around said center, fixed and rotatable orbit gears surrounding said carrier, a planet pinion meshing with said orbit gears, said planet pinion having a straight walled pocket in each end face, a mounting sleeve extending through said pinion for retention by said carrier, and bearing means adapted to roll along and in contact with the straight walls of said pinion, as well as in contact with said sleeve and carrier, to transmit to said carrier the axial component of the forces imposed 15 upon said pinion.
